UNITED STATES PATENT OFFICE.

FREDERICK R. S. DITMARS, OF KANSAS CITY, MISSOURI, ASSIGNOR TO CLARK MAILING MACHINE COMPANY, A CORPORATION OF MISSOURI.

STAMP-AFFIXING AND ENVELOP-SEALING MACHINE.

1,319,676.

specification of Letters Patent.

Patented Oct. 21, 1919.

Application filed July 17, 1918. Serial No. 245,319.

To all whom it may concern:

Be it known that I, FREDERICK R. S. DITMARS, a citizen of the United States of America, residing at Kansas City, in the county of Jackson and State of Missouri, have invented certain new and useful Improvements in Stamp-Affixing and Envelop-Sealing Machines; and I do hereby declare that the following is a full, clear, 10 and exact description of the invention, reference being had to the accompanying drawings, forming a part of this specification.

This invention relates to certain improvements in stamp-affixing and envelop-sealing machines wherein the successive operations 15 of moistening the flap of the envelop and subsequently the surface of the envelop to receive the stamp, then cutting the stamp from the strip of stamp material, then 20 affixing the stamp to the envelop and sealing the flap in an automatic sequence are performed, and it has for its object:

First, an upward adjustment of the moistening devices for the flap of the envelop, 25 whereby complete contact with the flap is assured.

Second, to provide for adjustment of the supporting plates for the stack of envelops, varying in length and width.

Third, to adjust the pressure of the preliminary envelop-holding or retaining devices.

Fourth, to adjust the position of the envelop-holding or retarding devices, to 35 accommodate the varying width of envelops.

Fifth, to enable the return movement of the finger bars out of contact with the envelop.

Sixth, to control the rapidity of action of 40 the stamp-separating devices, and simplify the actuating mechanism.

Seventh, the control of the actuating mechanism of the stamp separator from the reciprocating envelop-feeding carriage.

Eighth, to govern the operation of the stamp-separating and affixing devices responsive to the thickness or bulk of the envelop, when moved forwardly toward said devices.

Ninth, the automatic regulation of the feed of the stamp material, during the initial, forward movement of the envelop; and 50 Tenth, to effect the sealing of the envelops,

during the envelop-moistening and stamp-affixing operations. 55

The invention consists in the novel construction and combination of parts, such as will be first fully described, and then specifically pointed out in the claims.

In the drawings:

Figure 1 is a plan view of the stamp-affixing and envelop-sealing machine, embodying the invention, a portion of the stationary plate supporting the stack of envelops to be sealed and stamped, and the envelop-feeding plate beneath being broken away, to show the flap-moistening roller and the adjustable water reservoir.

Fig. 2 is a plan view of the operative parts of the machine, beneath the bed plates upon 70 which the envelops are carried forward, and the stationary supporting plate for the stack of envelops below the dotted line 2, 2, in Fig. 5, showing the reciprocating carriage, and the envelop-feeding plate, the track rails 75 supporting the carriage, the motor, and the carriage-actuating devices driven by the motor.

Fig. 3 is a side view of the stationary and operative parts of the machine, as seen upon 80 the removal of the vertical side plate, on the left-hand side of the machine, its outline being shown in dotted lines, showing the long arm on the rock shaft, controlling the action of the stamp-separating and 85 affixing devices, and controlled by the reciprocating carriage in its forward movement.

Fig. 4 is a transverse, vertical, sectional view, taken on the line 4, 4, in Fig. 1, looking forwardly, showing the transverse connecting plate, with the side plates of the frame, also showing the rock shaft carrying the retarding fingers to the envelops, the adjustable envelop feed rollers and the transverse bar supporting the extensions of the 95 bed plates.

Fig. 5 is a longitudinal, vertical, sectional view, taken through the bed of the machine on the line 5, 5 in Fig. 1, looking in the direction of the right-hand side plate of 100 the machine, showing the envelop-moistening and stamp-affixing mechanism, and the adjusting device for the water reservoir.

Fig. 6 is a longitudinal, sectional view, taken through the bed of the machine, taken 105 on the line 6, 6, in Fig. 1, showing the en-

velop-supporting plate, the reservoir for the water, and one of the bed and envelop-sealing plates.

Fig. 7 is a transverse, vertical, sectional view of the machine, taken on the line 7, 7, in Fig. 1, and looking in the direction of the rear end of the machine.

Fig. 8 is a detail side view of the reservoir for the water, showing the means for moving the forward end of the reservoir upwardly.

Fig. 9 is an isometric view of the water reservoir, showing the moistening roller, and means for preventing back rotation thereof.

Fig. 10 is a view, in perspective upon an enlarged scale, of a portion of the side plate on the left-hand side of the machine, showing a portion of the reciprocating carriage frame, and a portion of the forward rock-shaft and envelop-ejecting finger bar and the rock shaft devices on the said shaft, and the side of the machine for depressing the finger bar below the envelop in a return movement of the carriage frame, the view showing the position of the finger bar in the forward movement of the reciprocating carriage.

Fig. 11 is a detail view, in perspective, of the moistening receptacle for moistening the outer face of the corner of the envelop which receives the stamp, showing a portion of the side bar of the reciprocating carriage and the operating wedge or cam.

Fig. 12 is a side view, in detail, of the carrier for the stamp material, and the guide rollers, also showing the reciprocating carrier for the stamp feeders, and the inclosing hood, and the guiding plate for the stamp material beneath the stamp feeders, in longitudinal, vertical section.

Fig. 13 is a detail view, in perspective, of the carrier for the stamp material, and the hood within which the carrier has a reciprocal movement, showing the sight openings.

Fig. 14 is an isometric view of portions of the carrier for the stamp feeders, and the pivotal support for said feeders, and a portion of the pitman operating the carriers.

Fig. 15 is a detail side view, enlarged, of the vibrating track bar and rod actuating the stamp-separating cutter bar, and showing the spring supporting the forward end of the track bar, and the adjustable tension devices for the spring.

Fig. 16 is a view, in perspective, of the horizontal plate on the side member of the frame of the machine, carrying the stamp-supporting and stamp-feeding devices, showing in detail the stamp-supporting devices on the plate.

Fig. 17 is a view, in perspective, of the track plate operating the stamp-separating

and affixing lever, showing the plate-guiding devices.

Fig. 18 is a view, in perspective, of a portion of the side member of the frame of the machine, upon which the stamp-supporting, stamp-feeding and stamp-separating and affixing devices are located, showing a portion of the rock shaft actuating the stamp-feeders, also showing the arm on said shaft, with which the feed-adjusting catch bar is pivotally connected, and the lever support on the side member, and the adjusting device on the catch bar movable toward and away from the support, and controlling the action of the catch bar in its engagement with the stamp-affixing lever.

Similar numerals of reference indicate corresponding parts in all the figures of the drawings.

The frame of the machine, as seen in the drawings, to which reference is made, is rectangular in form, and comprises the longitudinal side plates or member 20, 20', on the respective right and left-hand sides of the machine, which extend upwardly a considerable height.

At the forward end of the frame is a transverse connecting bar 21, connected at its ends with the respective side plates 20, 20', at a distance upwardly from the lower surfaces of said side plates, approximately that of one-half their full height, the upper end portions of said side plates being cut away diagonally, as seen at 20', in Figs. 3 and 4. At the rear end of the frame is a transverse connecting bar 22, its upper surface being in line horizontally with the upper surface of the transverse bar 21. The frame of the machine is supported by the legs 23, 23', secured at their upper ends to the lower, inner portions of the respective side plates 20, 20', and adjacent the end portions of said plates.

Parallel with and a short distance inwardly from the inner surfaces of the side plates 20, 20', are the respective horizontal track rods or rails 24, 24', the rod 24' being located farther inwardly from the side plate 20' than the rod 24, from the side plate 20. The ends of the rods 24, 24' are secured rigidly to the respective transverse bars 21 and 22, between the lines of their upper and lower surfaces.

The bed of the machine, upon which the envelops are supported in a movement coincident with the various operations of moistening the surface affixing the stamps and sealing the flaps of the envelops, consists of a number of longitudinal flat strips or slats 25, 25', 25², 25³, extending parallel with the side plates 20, 20', of the machine, and having longitudinal spaces 25⁰, of the same width between each other. The strip 25, adjacent the side plate 20, is narrow in width.

and is arranged with its outer, longitudinal edge at a short distance inwardly from said plate. The next strip 25' is of an increased width to the strip 25, and the width of the strip 25² is in excess of the width of strip 25', the strip 25³, being narrow in width and arranged between the strip 25² and the side member 20', of the frame of the machine, and a considerable distance therefrom.

10 The rear ends of the separate bed strips 25, 25', 25², 25³, are connected rigidly with the upper surface of the rear, transverse connecting bar 22, the forward ends of said strips or slats extending forwardly the 15 width described, a distance considerably less than one-half the distance from the transverse bar 22 to the transverse bar 21, at the forward end of the machine. The forward ends of said strips or slats are reduced in 20 breadth or drawn out to form rods 26, which extend forwardly and downwardly, as further described.

Extending in a transverse direction to the frame of the machine, and connected rigidly 25 at its upper end portions with the inner surfaces of the side plates 20, 20', at points on said frame a short distance forward of 30 vertical lines on said sides, intermediate their respective ends, is a plate 27, extending in width from the line of the upper portions 35 of the side plates 20, 20', downwardly a short distance above the lines of the upper horizontal surfaces of the bed strips or slats 25, 25', 25² and 25³, to permit of the passage 40 thereunder of the envelops, as they are fed, one at a time, from the stack of envelops, which stack is supported by the said plate in one direction.

In the lower portion of the plate 27, adjacent 45 the inner surface of the side member 20, of the frame, is a vertical space or opening 27', and in the other lower end portion of said plate is a wide opening 27^x, which will be further referred to. The rods 50 26 which form a part of the bed strips 25, 25', 25² and 25³ or extensions thereof above referred to are triangular in cross-section (see Fig. 4), and are extended forwardly beneath the transverse plate 27, and a short 55 distance forward of a vertical line extending through said plate, as seen in Fig. 3, and are bent in a curved line, and connected integrally with a transverse bar 28, which bar extends in length nearly to the respective 60 track rods 24, 24', and is secured by the screws 28' to the upper surface of a transverse plate or bar 29, the ends of which plate extend below the rods 24, 24', respectively, and are bent at an angle at 29', and 65 secured rigidly to the side members 20, 20', of the frame, respectively.

30 indicates the envelop guiding roller, which is located in rear of the transverse plate 27, the lower surface of the roller be-

ing normally in line with the lower edge of the said plate 27, and adjacent the opening through which the envelops are fed in succession.

The roller is preferably made with a covering of rubber. The ends of the roller extend to the line of the inner sides of the openings 27', 27^x, of plate 27, and are journaled in the rear ends of the bars 31, 31', (see Figs. 3 and 5), which pass through said openings 27', 27^x, the forward ends of the bars extending forward of plate 27, being upwardly inclined and pivotally connected at 31^x, to the side member 20, of the frame. The bar 31' is bent at right angles immediately forward of plate 27, and extended to 75 the side member 20' of the frame, as seen in Figs. 1 and 4, thence extended along said side member and inclined upwardly and pivotally connected at 31°, with said side member, so that the gravity of the roller causes 80 it to bear upon the envelops, as they pass beneath. The envelops are moved forwardly over the bed of the machine, by means of a reciprocating envelop-feeding carriage, which consists of the forward, perforated 85 blocks 32, slidably mounted on the respective track rods 24, 24', and the rear, perforated blocks 33, also mounted slidably on the respective rods, and arranged a distance apart on said rods for reciprocating, respectively, to the ends of said track rods.

With the upper surfaces of the respective forward and rear blocks 32 and 33, on the respective track rods 24, 24' are connected the ends of the respective narrow connecting 100 plates 34 and 35, respectively. At the rear end of the carriage frame is a transverse connecting bar 36, connected at its ends with the lower surfaces of the blocks 32, 33.

On the forward surface of bar 36, and near each end, are the brackets 37, 37', which extend downwardly below the lines of the bar (see Fig. 10), and in said brackets are journaled the pins 38', on the ends of the rocking slat 38. 39 indicates a rocking slat, 110 which is journaled in the downwardly-extended plates 40, 40', secured to the inner surfaces of the respective connecting bars 34 and 35, at a point on said bars approximately one-third the distance from the rear 115 ends of said bars, toward their forward ends.

With the upper surface and forward portions of the rocking slat 38 are connected rigidly the lower end portions of the envelop-feeding finger bars 41, the upper portions of which bars extend in an upward and rearward direction over the upper surface of the transverse bar 36, and move with the forward movement of the carriage frame, in the openings or spaces 25, between 120 the slats 25, 25', 25² and 25³, forming the bed of the machine, and in the rearward movement of the carriage are depressed be-

low the line of the lower surfaces of the said slats, in the manner further described. In the lower surface of the finger bars are envelop-engaging notches 42 (see Fig. 10).
 5 Upon the rocking slat 39 are envelop-feeding finger bars 43, which are precisely the same as the finger bars 41, the notches enabling the envelops to be positively held, when engaged therewith. Upon the lower surface of the rocking slats 38, and at the end adjacent the side member 20, of the frame of the machine, is secured an arm 44, extending downwardly and forwardly a short distance, and upon its lower end is a pin 45, extending toward the member 20, of the frame.

Upon the inner surface of said member 20 of the frame in the path of movement of the pin 45, on the arm 44, is a horizontal 20 tripping plate 46, having a flange 47, upon the inner surface and forward end of said plate, extending downwardly and pivotally connected to said side member at 46°.

When the carriage is at the end of its forward movement the pin 45 passes the pivotal point 46°, to a position beneath the plate 46. A pin 48 is secured to the side member 20, a short distance in rear of the pivotal point 46°, of flange 47, with the said side member 20, which supports the tripping plate in a normal, horizontal position. The rear end of the trip plate is curved at 46°, downwardly (see Fig. 10), and upon the pin 45 on the arm 44 passing beneath said 35 curved end of the trip plate, said plate is raised from the pin 48, and in the forward movement of the carriage the pin 45 moves upon the upper surface of plate 46, raising the finger bars 41. A like tripping plate 49 is pivoted to the side member 20, in the path of movement of the pin 50°, on the arm 50, on the rocking slat 39 (see Fig. 2), which is precisely the same as plate 46, and operates in the same manner to raise and 45 depress the finger bars 43, as described of the finger bars 41. An envelop-feeding plate 51 is connected rigidly at its forward end with the longitudinal plates 34 and 35, of the reciprocating carriage, at points on said 50 plates intermediate their forward and rear ends, the forward end of said plate extending forwardly to within a short distance of the forward ends of the plates 34 and 35. The rear edge of the plate 51 is very slightly 55 bent upwardly at 51°, and engages with the flap of the envelop in the initial forward movement of the reciprocating carriage. Upon the lower surface of said rear edge of the plate 51 is a moistening strip 51°. In 60 the rear portion of the feed plate 51 is a slot 51°, for the purpose further explained. The moistening device for the flaps of the envelops consists of a triangular shaped hollow receptacle 52 (see Fig. 9), having a 65 flat top plate 53, side members or plates 59,

which are bent inwardly at 59°, 59°, to decrease the width of the box, and a rear end 60, a forward end 61, and a bottom member 62, all of the parts being soldered together, hence water-tight.

In the rear portion of the top plate 58 is a transverse opening 63, and within the receptacle beneath said opening is a moistening roller 64, journaled at its ends in the grooves 58°, in the side members 59, of the 70 said receptacle, the outer portion of the roller extending through the opening 63, a covering of felt or cloth 65, extending around the roller, for moistening the strip 51° of the feed plate, in a reciprocal movement of the carriage. A wire 66 is wound about the roller 64, its free end 67 being extended within the vertical groove for the journal of the moistening roller, whereby its forward rotation is limited. The water 80 may be supplied to the receptacle through the opening 63. The bottom 62 of the receptacle, in the direction of its end member 61, is supported adjustably upon the outer ends of the arms 68, on a rock shaft 69, the 85 ends of which rock shaft being journaled in the side members 20, 20°, respectively, of the frame of the machine (see Figs. 2 and 5). With a separate arm 70, on the rock shaft 69, adjacent the side member 20° is 90 pivotally connected the end of an adjusting rod 71, which extends upwardly a short distance, and is bent at right angles, the outer end being extended forwardly through the transverse connecting bar 21, 95 at the forward end of the frame of the machine.

Around this rod 71 extends a coiled spring 72, the rear end of which spring is held by a ring 73, fixed to said rod, the forward end 105 of the spring bearing against the inner surface of the bar 21. The end portion of the rod 71 extending through bar 21, is screw-threaded, and upon said end is an adjusting nut 74, for raising or lowering the receptacle 110 the proper degree. Upon the forward end 65, of the receptacle 52, are separate angle bars 74°, 74°, with which bars are connected the respective ends of a rod 75. Upon the inner surface of the transverse bar 21, at the forward end of the frame, is secured a flat bar 76, the ends 77, of which are bent outwardly, at right angles to said bar 21, and provided with grooves 78, which grooves receive the rod 75, on the angle bars 74°, 74°, 115 120 of the receptacle, and support said receptacle removably in place. At the forward end of the side members 20, 20°, of the frame are secured by the vertical flanges 79°, the respective horizontal, inwardly-extended ledge plates 79, upon which is arranged the respective ends of the horizontal envelop-supporting plate 80.

On the forward surface of the transverse bar 21 is an upwardly-extended lug 81, upon 125 130

which the forward end of plate 80 rests, the said portion of plate 80 being bent at right angles, and extended downwardly past the forward surface of the lug, and provided 5 with a longitudinal opening 82. In the lug 81 is a screw-threaded pin 83, upon which is a nut 84, securing the plate 80 in a fixed position. The rear portion of the plate 80 extends to a position in a vertical line with 10 the moistening roller 64, the rear end portion of which plate is bent or inclined downwardly, in a slight degree, at 80°, and upon which bent portion the stack of envelopes is mainly supported. The devices for holding 15 the envelopes, when arranged upon plate 80, from a forward or end-wise movement in a stack, consist of upright plates 84 and 85, upon the upper surface and rear portions of plate 80, these plates being spaced apart, 20 and arranged in the longitudinal direction of the frame of the machine, and provided with forward, inwardly-bent portions 84^x, 85^x, respectively. At the lower end of the said portions 84^x, 85^x of plates 84 and 85 are 25 forwardly-extended flanges 86 and 87, respectively, the former plate 84 being secured to the right-hand side of the plate 80, a considerable distance inwardly from the side member 20', of the frame of the machine, 30 by the screws 86^x, which pass through the flange 86, into said plate 80. In the envelop-supporting plate, extending beneath the flange 87, on the lower end of the portion 85^x of plate 85, is a slot 88, extending 35 nearly to the left-hand end of said plate 80, and in said flange 87 is a slot 89, extending in the same direction. An adjusting bolt 90 (see Fig. 6) extends upwardly through slots 88, and 89, and is provided with an adjusting nut 90'. A short distance above the 40 vertically movable feed roller 30 is a rocking bar 91, square in cross-section, upon the end portion of which bar are pins 91', which are journaled in the side members 20, 20', 45 of the frame of the machine (see Fig. 4).

Upon the end portion of bar 91, adjacent the side member or plate 20, is secured by the adjusting screw 92^x, an arm 92, through the outer end portion of which arm extends 50 an adjusting screw 93. The lower end of screw 93 bears upon the inwardly-extended portion of an angle plate 94, secured to said side member 20, in which plate is a slot 95, which permits lateral adjustment of arm 92 55 (see Fig. 1). In the adjustment of the arm 92, on angle plate 94, a slight oscillation of the bar 91 is permitted. To the bar 91 is secured, in like manner, to the arm 92, the inner ends of separate arms 96 and 97 (two 60 being shown) one intermediate the ends of said bar, and the other a considerable distance inwardly from the side member 20', of the frame of the machine.

Upon these arms 96 and 97 are adjustably 65 supported by the adjusting screws 98', 97',

respectively, the envelop-holding and retarding plates 98 and 99, respectively. These plates 98 and 99 are nearly square in form, and are provided with a downwardly extended portion, which rests upon 70 the upper surface of the feed plate 51, in its rearward movement, and are supported above the bed plate extensions 26, in the forward movement of the plate 51. In the lower, forward portion of said envelop-retaining plate is a notch 100 (see Fig. 6). The adjusting screws 98', 99' enable the plates to be moved rearwardly or forwardly, as the retardation of the envelop is desired, the notched portions of which plates engage 80 with the envelopes, as they move forwardly, in succession.

The moistening device, for moistening the outer surface of the envelop, consists of a square box-frame 101, seen in detail in Fig. 11, and is open at the top and bottom, and in which opening is a closely-fitting sponge 102, projecting a short distance from the open, lower end of the box-frame 101. This box-frame is located in position directly above the extension rod 26, from the bed plate 25^a, and beneath which box-frame the right-hand portion of the feed plate 51 has a reciprocal movement. Upon the outer side and upper end portion of the box-frame 95 is an outward extension or block 102', with which block is connected rigidly the inner end of a supporting bar 103, which is extended toward the side member 20', of the frame of the machine, thence bent at right 100 angles and extended forwardly, parallel with said side and connected pivotally with said side member, at 103^x. The downward movement of the moistening box is effected by a wire spring 104, one end of which 105 spring extends within the opening 27^x of the transverse plate 27, and bears against the upper portion of said opening. The other end of said wire spring extends to and around the pivot 103^x, for the bar 103. It 110 is then extended along said bar and extended within an opening 105 in said bar.

Extending outwardly from the lower portion of the box-frame 101 toward the side member 20', is a plate or flange 106. Upon the upper surface and right-hand side of the feed plate 51, and intermediate at its ends, is an upwardly-extended wedge-shaped plate or cam 107, which in the rearward movement of the feed plate comes in contact with the inwardly-extended portion of the arm 103, on the moistening box 101, and imparts to said box-frame an upward movement. The locating of the cam 107, on the feed plate, is such that in the completion of the movement rearwardly of the reciprocating carriage, the highest point of the wedge is reached, and the full elevation of the box-frame 101 against the tension of the spring 104. 120 125 130

The reciprocation of the envelop-feeding carriage is effected by means of a large, horizontally-positioned, grooved wheel 108, located directly beneath the flap-moistening receptacle or box 52. The wheel 108 is provided with a downwardly-extended shaft 109, journaled in a shaft bearing 110, secured rigidly to the forward side of a transverse bar 111, intermediate its ends. The 10 ends of the bar 111 are bent at right angles, and secured to the side members 20, 20', of the frame of the machine at 112.

113 indicates a crank shaft, one end of which shaft is pivotally connected at 113', 15 with the upper surface of the peripheral portion of the large wheel 108. The rear end of the crank shaft 113 extends forwardly in an upwardly-inclined direction to within a short distance of its forward end, 20 and is then bent at a greater angle, and thence horizontally, and connected pivotally at 114, with the lower surface of the transverse connecting bar 36, of the reciprocating carriage, at a point intermediate the ends 25 of said bar.

In the one rotation of the wheel 108, the reciprocating carriage completes its forward and rearward movement.

115 indicates an electric motor, of small power, located near the forward end of the sides 20, 20', of the frame of the machine, and upon the upper surface of a transverse plate 116, having flanges 116', secured to the lower portions of said side members 20, 20', 35 immediately above the lower surface of said plates.

117 indicates the motor shaft, and 118 a small, grooved wheel on said shaft. 119 indicates an endless band, extending over the 40 grooved wheel 118, and also over the larger grooved wheel 108.

120 indicates the electric conducting wires leading from the motor to the switch 121, and from switch 121 the wires are extended 45 at 122, and provided with a screw-threaded plug 123, which is fitted within any socket in an electric supply system, and with this power the operation of the machine is rapid and a high degree of efficiency obtained.

50 The stamp-supporting and stamp-feeding devices are located in position directly above the slat 25', on the right-hand side of the bed of the machine. The support for said devices consists of a horizontal plate 124, 55 extending parallel with the side plate or member 20', of the frame of the machine, and from said side member inwardly to a position a short distance above the slat 25', of the bed of the machine, the inner surface 60 being in a vertical line with the inner surface of said slat.

The plate 124 is provided with a flange 125, on its inner portion which extends upwardly and is secured to the side member 65 20', of the frame of the machine (see Fig.

16). The plate 124 extends from a point a short distance inwardly from the line of the rear end of side member 20', of the frame, forwardly to a point a short distance rearwardly of a vertical line extending through 70 the forward end of the bed slat 25', and integral with its inner portion is an angle plate 125', extending upwardly and connected with the frame 124. Within the outer, beaded edge 124', of plate 124, is a 75 longitudinal track plate 126, extending upwardly a short distance. A like track plate 127 extends longitudinally with plate 124 and is located intermediate the track plate 126 and the upwardly-extended flange 125. 80

The supporting devices for the stamp material consists of an upright plate 128 (see Fig. 16), adjacent the inner side of the track plate 127, and arranged a short distance inwardly from the rear end of the 85 plate 124. Upon the lower end of plate 128 is a flange 129, secured fixedly by a screw 129', to the plate 124. A screw bolt 130 extends through the upper end of plate 128, upon which is a thimble 131. A bar 132 is 90 secured at its upper end to the inner end of the screw bolt 130, by a nut 133 (see Fig. 1).

Upon the thimble 131 is arranged a retaining disk 134, for the roll of stamp material. A wire 135 secured at its outer ends 95 to the outer surface of the disk, engages the screw bolt between its head and the thimble 131. Upon the outer end of the bar 132 is a screw bolt 136, carrying a thimble 137. A portion of the plate 128 is bent outwardly 100 at 139, to which is secured the upper end of a spring plate 140, which extends downwardly, and its outer end curved upwardly and brought in contact with the thimble 137, on the bar 132. 105

The stamp material employed in the machine consists of a narrow strip of paper 141, of the usual description, upon which official stamps are printed in ribbon form, and perforated transversely between the 110 stamps and the stamp ribbon wound in a roll and placed in the sleeve 131, and held thereon by the disk 134. One surface of the strip is printed with the stamp, and upon the other is an adhesive substance. 115

Upon the upper surface of the plate 124, forward of the plate 128, and between the flanges 126 and 127, is located a yielding plate 142, for the stamp material, its inner edge portion 143 extending upwardly, and hooked over the flange 127, and secured thereto supporting the guide plate 142, a slight distance above the plate 124. Spring extensions 142' extend forwardly from the plate 142, to the forward end of plate 124. 125 The free end of the stamp material is extended downwardly from the roll, and rearwardly between the thimble 137 and the curved portion of the spring plate 140, thence downwardly over the curved edge of 130

the spring plate to the plate 124, thence forwardly beneath the guide plate 142, and is fed, as further described.

At the forward end of the horizontal supporting plate 124, and integral with its outer edge portion are the upwardly-extended flanges 144 and 145.

The stamp-feeding devices consist of a reciprocating carrier 147, its frame being composed of parallel wide strips 148 and 149, secured together by a longitudinal flat plate 150, integral with the upper surfaces of the respective strips (see Figs. 12, 13, and 14). In the rear, upper portion of plate 150 is a longitudinal slot 151. The carrier 147 is arranged to slide within a fixed hood 152, of an increased length to the carrier, and which is mounted on the forward end of the plate 124, secured to the side member, 20 of the frame of the machine.

The hood 152 consists of a horizontal plate 153. Connected with its outer edge is a side member 154, which extends downwardly to the line of the outer edge of plate 124 and 25 past the outer surfaces of the flanges 144 and 145, to which flange 145 the hood is rigidly secured by a screw 146.

An inner side member 155, of the hood, extends downwardly toward the plate 124, 30 and is bent inwardly to form a guide flange 156, which rests upon the flange 127 on the plate 124. From the inner surface of the top plate 153, a short distance inwardly from the side plate 154, extends downwardly 35 a longitudinal plate 157, provided with an inwardly-extended flange 158, which rests upon the flange 126, on the plate 124. The carrier 147 is movable between the plates 155, 157, supported by the guide flanges 156, 40 158, respectively, to the line of the forward end of the hood, in a forward movement of the carrier.

The stamp-feeders consist of a number of flat plates 160, their outer ends being cut 45 away from the line of their upper edges, downwardly and diagonally, terminating in a forwardly-extended point, adapted to engage with the perforations in the stamp material. These feeding plates are arranged 50 loosely upon a rod or pin 161, extending through registering openings in the rear ends of the plates, the ends of the pin 161 being secured within the sides of the longitudinal strips 148, 149, intermediate the top 55 plate 150, and the lower edges of the respective strips, and a short distance inwardly from their forward ends.

In the top plate 153, of the hood, and near its forward end, is a sight opening 162, 60 through which the position of the feeder plates may be observed, with respect to the perforations in the paper, upon a movement rearwardly of the feeders, to engage with the said perforations.

65 In the rear portion of the top plate 153,

of the hood, is a longitudinal opening 163, which is directly above the opening 151, in the plate 150, of the carrier, and through which openings extends the inner end of a pitman or bar 164, which is pivotally connected 70 with a pin 165, connected with the respective side strips 148 and 149, of the carrier, at short distances inwardly from their respective ends. A rock shaft 166 operates the carrier for the stamp-feeders, one 75 end of which shaft extends in a transverse direction to and a slight distance above the rear end portion of the plate 142, supporting the stamp-feeding devices, and immediately in rear of the vertical plate 128, supporting 80 the stamp-supporting devices, and is journaled at 166^x, in the upwardly-extended flange 125, on said plate. The other end of the rock shaft extends transversely to the bed of the machine, and is journaled in the 85 side member 20, of the bed of the machine.

Upon the rock shaft 166, in rear of the stamp-feeding devices is fixed an arm 167, which extends upwardly a short distance. With the upper end of arm 167 is pivotally 90 connected the rear end of the pitman 164, operating the stamp feeders.

Upon the end-portion of the rock shaft 166, journaled in the side member 20, of the frame of the machine, is a downwardly and 95 rearwardly-extended arm 168, having a curved lower edge.

170 indicates a lever on the left-hand side of the machine, seen in Figs. 1 and 3, which operates the arm 168, on the rock shaft 166. 100 The lever consists of a long bar, its forward end extending forwardly beneath the angle plate 94, and is pivotally connected at 171, to the side member 20, of the frame of the machine. The rear end of the bar or lever 105 extends rearwardly to within a short distance of the transverse bar 22, at said rear end of the frame of the machine, directly beneath the arm 168, and is bent downwardly in a gradually-curved line. The 110 rear end of the lever 170 is retained against the side member 20, of the frame of the machine, by means of the upright guide plate 172, on the rear end of the longitudinal side plate 34, on the reciprocating envelop-feeding carriage, which actuates the lever 170, to raise its rear end, and cause the lever to move the arm 168, on the rock shaft 166, upwardly, and throw forwardly the upper end 115 of arm 167, and thus operate the stamp-feeding devices near the end of its rearward movement, when the curved end of said lever 170 is moved upwardly, and rests upon the upper surface of the narrow side plate 34, of the reciprocating carriage. Upon the 120 end of the shaft 166, journaled in the upwardly-extended flange 125, on the inner surface of the side member 20, of the frame of the machine, and adjacent said plate, is secured fixedly an upwardly-extended arm 125

130

173. A coiled spring 174 is wound around the shaft 166, one end of which spring is extended downwardly, and secured to the flange 129, on the lower end of the stamp-
 5 supporting plate 128, by the screw 129*. The other end of the coiled spring bears against the forward portion of the arm 173, the coiled spring acting to effect a return movement of the arm 167, operating the
 10 stamp-feeding device.

The stamp-operating and affixing devices consist of a flat bar or lever 175, one end of which bar extends through a vertical opening 175*, in the side member 20', of the
 15 frame of the machine, and which extends transversely to the outer surface of the angle plate 125', at the forward end of the plate 124, supporting the stamp-feeding devices. Said outer end of arm 175 is pivot-
 20 ally connected with a lug 176, on the outer surface of the side member or plate 20', of the frame of the machine, by the pivot bolt 176*. The inner end of the arm extends inwardly, in close contact with the outer sur-
 25 face of the angle plate 125', to a position opposite the forward end of the hood, and integral with the outer surface and lower portion of said arm is a laterally-extended, upwardly-inclined flange or plate 177. To
 30 the lower surface of said plate is secured, by the screws 179, a stamp-cutting and af-
 fixing plate 178, having a cutting edge 180, which comes into close position with the for-
 35 ward end of the plate 124, upon which the stamp material is fed.

With the outer side of the lever 173, at a point a short distance inwardly from the line of the inner surface of the side member 20', of the frame of the machine, is pivot-
 40 ally connected, at 180*, the upper end of a rod 180 (see Fig. 15), the lower end of which rod extends downwardly, through an opening 181, larger in circumference than said rod in the horizontally-extended portion
 45 of an angle plate 182, secured to the inner surface and lower portion of the side mem-
 ber 20', of the frame of the machine, and screw-threaded at the central and lower end-
 portions of the rod. Upon said rod is a tube
 50 184, the lower end of which tube extends through the opening 181, in the angle plate 182. Upon the lower screw-threaded end of rod 180 is a nut 185, which bears adjust-
 55 ably upon the lower surface of the horizon-
 tal portion of the angle plate 182. Upon the central screw-threaded portion of the rod is an adjusting nut 186, bearing on the upper end of the tube 184. Extending around the tube is a spiral spring 187, one
 60 end of which spring bears upon the upper surface of the horizontal portion of the angle plate 182, and the other end against the adjusting nut 186, whereby the tension of the coiled spring 192, further described,
 65 is increased.

The operating devices for the rod 180 consist of a horizontal track plate 188, narrow in width, and provided with an opening 189, at its forward end, through which the rod 180 extends. From the inner surface of 70 said end extends downwardly a guiding flange 190, which extends downwardly on the inner side member 20', of the frame of the machine (see Fig. 7). Said end of plate 188 is supported yieldingly, by the upper 75 end of a coiled spring 192, extending around the rod 180, and its lower end bears on the adjusting nut 186.

From the inner surface and rear end of plate 188, extends downwardly, a guiding 80 flange 193, and upon the side member 20, of the frame of the machine, is a keeper plate 194, which retains said plate normally against said side member 20. In the plate 188, inwardly from the flange 193, is a notch 85 195.

196 indicates a vertically-positioned catch plate, within the notch 195, of the track plate 188, its upper end being pivotally connected at 196*, with the side member 20, of 90 the frame of the machine, a short distance above the line of the track plate, the pivot extending through said end of the catch plate immediately in rear of a vertical line passing through said plate, intermediate its 95 forward and rear surfaces.

In the rear portion of the catch plate is a notch 197, the lower edge of which notch engages in the normal position of the track plate 188, with the rear end of the notch 100 195, in said plate, and holds said plate in conjunction with the spring 192, in a normally-raised position.

The portion of the catch beneath the notch 197 is curved downwardly and forwardly at 198. With the inner edge of the longitudinal plate 35, of the reciprocating carriage, a short distance forwardly of the transverse connecting bar 36, is connected rigidly the upper end of a flat plate 199, the 110 lower end of which plate passes the inner surface of the track plate 188, and upon the inner side of said lower end of the plate is pivoted a roller 200, which moves over the lower surface of the track plate 188, when 115

^{stamp-separating affixing} devices are out of operation, and the envelop-feeding carriage moves forwardly and rearwardly.

The controlling devices which set in motion the stamp-separating and affixing de- 120 vices, are operable by the envelop fed by the reciprocating carriage, and consist of a rock shaft 201, one end of which shaft is journaled in the side member 20', of the frame of the machine, a short distance forward of 125 the stamp-affixing lever 173. The other end of said shaft extends in a transverse direction to the bed of the machine, and is journaled in the side member or plate 20, of the frame of the machine. Upon said shaft, ad- 130

5 jacent the side member 20', is secured fixedly to the forward end of a long lever 202, the rear end of which lever extends rearwardly and downwardly, and enters within a notch 203, on the upper, forward edge of the catch 196, located slightly below a line extending horizontally through the pivot 196* for said catch.

10 Upon the rock shaft 201 is secured adjustably, by the set screw 204*, one end of a controlling arm or lever 204, the other end extending rearwardly and downwardly upon the upper surface of the bed plate 25*, in the path of the envelops passing from the 15 stack, between the envelop-retaining plates 84 and 85.

20 The sealing devices for the flaps of the envelops consist of the longitudinally-extended narrow strips 205, which extend parallel with each other, upon the upper surface of 25 the respective bed plates 25, 25' and 25*, from the rear end of said plates, forwardly to a position a short distance from the envelop feed roller 30, and are curved upwardly at said end.

30 The forward portion of the sealing strips are supported by the transverse shaft 206, journaled at one end of the upright flange 145, on the outer edge and forward end of the supporting plate 124, for the stamp-feeding devices, the other end of which shaft 35 is journaled in the side member of plate 20, of the frame of the machine.

35 Upon the shaft 206 are adjustably connected the arms 207, having notched outer ends, with which are pivotally connected the upper ends of flat plates 208, which plates are rigidly connected with the upper surfaces of the respective sealing strips.

40 The rear portion of the strips are guided by the arms 209, loosely mounted on the rock shaft 166, which are the same as the arms 207, on the shaft 206, and which arms are pivotally connected with the fixed plates 45 210, on said sealing strips.

45 The means for regulating automatically the feeding of the stamp material, so that the stamp feeders will always move the length of the stamp and engage with the 50 perforations, consists of a catch bar 212, which is fixedly connected at its rear end with the upper end of the arm 173, and its forward end extends forwardly to a position above the stamp-affixing lever 175, and is 55 provided with a notch 213, engaging with the upper portion of said lever, whereby its movement is controlled until the said lever is withdrawn, so that the feed plates feed the stamp accurately, so that the engagement of the feed plates upon each return 60 movement meets the perforations of the stamp to be separated by the lever from the strip of stamp material. During the engagement of the notched bar 212 with the 65 lever, the arm 168 is elevated and inactive.

An angle plate 214, secured to the side member 20', of the frame of the machine, has its outwardly-extended portion extended beneath the catch bar, at a point intermediate the ends of said bar, a projection 70 215 extending upwardly from the outer portion of said support for the bar, and preventing disengagement.

Upon said catch bar is a sleeve 216, secured adjustably in position by a set screw 75 217, from which sleeve a gage plate 218, which gages the distance to and from notch 213, extends downwardly and comes into contact with the forward edge of the outwardly-extended portion of the angle plate 80 214. At the rear end of the frame of the machine and extending transversely to the side members or plates 20, 20', of the frame of the machine, is a bar 219, having portions 85 220, extending upwardly from the line of the lower edges of the respective plates 20, 20', and secured fixedly thereto. With the upper surface of said bar are secured fixedly the inner ends of the bars 221, which extend rearwardly a considerable distance therefrom, and outwardly from the rear ends of the sides of the frame of the machine, and with the ends of said bars is attached the lower surface of a vertical envelop-retaining plate 222.

90 To the upper surface of the bars 221 is secured the respective ends of a horizontal plate 223, upon which the envelops fall when ejected from the machine.

95 In operation the envelops to be stamped 100 are assembled in the proper quantity, flat-wise, with the flaps downward, and one envelop upon another to form a stack. The stack of envelops is then placed between the guiding plates 84 and 85, on the envelop-supporting plate 80, against the forward surface of the plate 27, with the rear portion of the lower envelop in the stack resting upon the inclined portion 80', of the envelop-supporting plate, hence it will be 105 observed that the lowermost envelop in the stack will fall into a like position with that of the said inclined portion of the supporting plate, the adhesive flap of the envelop being slightly below the plane of the forward edge 51', of the envelop-feeding plate 51, on the reciprocating carriage, which prior to the operation of feeding the envelops forwardly is at the limit of its forward movement as seen in dotted lines in 110 Fig. 1. In this forward position of the reciprocating carriage, the flap moistening lower surface 51*, on the envelop-feeding plate is vertically above the moistening roller 64, in the moistening receptacle 58, 115 and in contact therewith. This receptacle is filled with water, and as the roller 64 moves in a partial rotation with the contact of the flap-moistening portion 51*, of the envelop-feeding plate 51, the surface is kept con- 120 125 130

stantly moistened. The moistening roller 64 has a yielding contact with the forward flap moistening portion 51^x, of the envelop-feeding plate, through the spring 72, on the rod 71, which bears against the ring 73 on said rod and governs the upward movement of the moistening receptacle, and the contact may be increased and made more positive by the adjusting nut 74, on said rod, which actuates the arms 68, on the rock shaft 69, to raise the forward end of the moistening receptacle. The spring 72 simply keeps the tension on the rod 71 for its adjustment.

The sponge 102, in the spring-holding receptacle, is then moistened, and this moistening will suffice for moistening the outer surface of a large quantity of envelopes. Should the envelopes require longer space between the plates 84 and 85, the adjustment of plate 85 may be made any required distance from the plate 84, by releasing the adjusting nut 90, on the bolt 90, and the plate 85 moved laterally in the direction of the side member 20, of the frame 25 of the machine, to accommodate envelopes of various lengths.

The free end of the strip of stamp paper 141 is drawn from the roll on its supporting thimble 131, and between the roller 137 and the curved outer portion 136, of the spring plate 140, thence beneath said plate forwardly, beneath the stamp-guiding plate 142, the adhesive portion of the strip being downwardly. The free end of said strip is then extended beneath the spring extension 142^x, of the guide plate 142, and to a position in line with the forward end of the supporting plate 124, and also in which the forward individual stamp in the strip extends beneath the series of stamp feeders 160, the pointed ends of which feeders engage with the series of perforations between said stamp and the stamp in rear thereof.

The plate 218, on the catch bar 212 is positioned on said bar a distance rearwardly from the forward end of the notch 213, equal to the distance between the perforated portions of the stamp material toward and rear of an individual stamp.

While the outer end of the controlling bar 204, which controls the movement of the catch 196, of the stamp-affixing devices, remains in contact with the upper surface of the bed plate 25^x, the stamp-feeding and stamp-affixing devices remain inactive, and in the forward movement of the feed plate the notch 51^x thereon, permits a complete forward movement of the feed plate to be made, without coming into contact with the controlling bar 204, which enters said notch.

The envelop-holding and retarding plates 98 and 99 are adjusted in position on the respective arms 96 and 98, to meet the requirements in the diversity in lengths of envelopes, and for the ordinary length of

envelop, the fingers are seen arranged in their path of movement, and further act to hold the envelop from rearward movement, when the reciprocating carriage moves rearwardly, and leaves the envelop in position 70 to receive the stamp.

The power to operate the machine as referred to, is derived from the motor 215, and upon operating the switch 121, the current from its source is supplied to the motor 75 and motion imparted to the large drive wheel 108, on shaft 109, from the small grooved wheel 118, on the motor shaft 117, through the belt 119, and from the large wheel 108 through the pitman 113 to the 80 envelop-feeding reciprocating carriage.

The envelopes being stacked between the envelop-holding plates 84 and 85, and between their inner portions 84^x, 85^x, and the transverse plate 27, the envelopes are fed, one 85 at a time, from the stack, beneath the feed roller 30, in the forward movement of the reciprocating carriage, beginning with the lowermost envelop in the stack, which being inclined rearwardly and downwardly in the 90 path of movement of the rear edge portion 51^x, of the envelop-feeding plate 51, in the forward movement of said plate, the portion which receives moisture upon the strip 51^x, from contact with the moistening roller 64, 95 enters between the flap and the adjacent surface of the envelop, the adhesive surface of the flap of the envelop receiving moisture from the strip 51^x, and the envelop is simultaneously carried forward during one-half 100 the circle of rotation of the wheel 108, beneath the finger plates 98 and 99 and beneath the forward, upwardly-curved ends of the sealing strips 205, which are raised slightly upwardly thereby into a position in which 105 the feeding end of the feed plate 51 and the envelop come directly beneath the stamp-separating and affixing devices, the wheel 108, in the meantime, having made one-half 110 its circle of rotation in its rearward movement, thereby placing the right-hand corner of the envelop in a position on the slat 25^x, of the bed of the machine, directly beneath the stamp-cutting and affixing plate 178, 115 on the lever arm 175, the notched rear ends of the finger plates 98 and 99 then falling from the envelop upon the feed plate 51, in rear of the envelop, and preventing its rearward movement.

In this single, forward movement of the 120 feed plate 51, with the envelop, the upper surface and right-hand end portion of the envelop passes in contact with the sponge 102, in the sponge-holding receptacle, and is moistened, and the envelop upon the feed 125 plate contacts with the outer end of the arm 204, on the rock shaft 201, moving said arm upwardly a slight distance, and causing the long arm 202, on shaft 201, within the notch 203, of the catch 196, to move upwardly and 130

disengage said catch from the rear end of the notch 195, in the track plate 188, during which time the roller 200, on the depending bar 199, on the reciprocating carriage, has 5 passed on the under surface of the track plate 188, and outwardly from the rear end of said plate, which then falls upon the guide plate 194, and the roller 200 is in position to make its return movement upon the 10 upper surface of said track plate. Simultaneously with this forward movement of the reciprocating carriage, its forward end acts upon the rearwardly curved end of the lever 170, to raise it upwardly into contact 15 with the arm or cam 168, and impart movement to the rock shaft 166 and arm 167, actuating the pitman 164 and the stamp feeders 160, move an exact distance forwardly upon the plate 124, to move the first stamp 20 forwardly beyond the forward end of said plate, into position above the envelop, the notch 213, in the bar 212, engaging with the stamp-affixing lever arm 175, and holding the arm 168 in an elevated position. In the 25 next half circle of rotation of the wheel 108, and as the reciprocating carriage begins its forward movement, the arm 168 moves downwardly, and the spring 174, on the rock shaft 166, acts to cause a return movement of the arms 167 and 173, on shaft 166, and the return movement of the carrier 147, and the feeders 160, which immediately engage with the perforations in the strip of the stamp material, in rear of the stamp, 30 which has been moved forwardly and separated from the strip and affixed to the envelop. Should the bar 212 fail to engage the stamp-affixing lever arm, the spring 174 on the shaft 166 acts to hold the arm 173 in 35 a rearward position, and the catch bar 212 out of engagement with the lever 175 of the stamp-affixing devices, and the arm 168 on the shaft 166 ceases to operate the pitman 164, and the stamp-feeding devices remain inactive. In this return movement 40 of the reciprocating carriage, the roller 200 moves upon the track plate 188, in the direction of the forward end of the plate compressing the spring 192, and forcing the rod 180 downwardly, and drawing down the outer end of the lever arm 175, from the notched bar 212, and the spring 174 and shaft 166, move said bar and the feeding devices into contact. The cutter plate 178 moving in close contact with the forward edge of the plate 124, supporting the stamp-feeding devices, cuts away the 45 first stamp presented, and extending over the envelop along the line of the perforations, and in the downward pressure of the said plate 178, upon the stamp affixes the stamp to the moistened surface of the envelop. In this return movement of the reciprocating carriage, the envelop-feeding 50 plate is immediately withdrawn from the 55 envelop, the pins 50*, on the arm 50, on the rock shaft 39, and the pin 45 on the arm 44, on the rock shaft 38 move upon the lower surfaces of the respective tripping plates 46 and 49, and cause the outer ends of the finger bars 41 and 43, on the respective rock shafts 38 and 39, to move downwardly out of contact with the envelops, and leaving the envelop upon the upper surface of the plate 25*, 25*, of the bed of the machine, and held 60 by the weight of the sealing plates 205 from movement. The reciprocating carriage having completed its return movement, the pins 50*, on the arm 50, on the rocking slat 39, and the pin 45 on the arm 44, on rocking 65 slat 38, raises the rear curved ends of the respective tripping plates; which fall immediately in position so that said pins 50* on arm 50 and the pin 45 on the arm 44 will move over said curved ends and raise the finger bars in an upward position, in readiness to move forward another envelop in the direction of the stamp affixing devices. The reciprocating carriage again moves forwardly, feeding forward another envelop 70 beneath the feed roller 30, into a position in which it is held by the retarding plates 98 and 99, and at the same time the forward finger bars 41 come into contact with the rear portion of the stamped envelop and 75 forces said envelop rearwardly between the sealing strips and the rear ends of the slats forming the bed of the machine, the downward pressure of the sealing strips 205 being sufficient to cause the adhesive, moistened flap of the envelop to close firmly and seal itself, and the envelop is ejected from the rear end portions of the slats, and falls upon the plate 223, of the envelop support 80 at the rear end of the machine. The succeeding envelops, when stamped fall one upon another, from the bed of the machine. 85

In this machine, the rapidity of movement of the reciprocating carriage feeds an envelop to its position to affix the stamp, as a 90 prior stamped envelop is sealed, and discharged from the machine, hence the capacity of the machine to seal and stamp the envelops is greatly increased, the envelops being fed toward the stamp-affixing and sealing devices in succession, with rapidity and accuracy in movement, the succession of envelops keeping the controlling lever or arm 204 constantly raised in position, and while the arm remains so, the stamp-feeding and stamp-affixing devices are in coöperation 95 with the envelop-feeding devices.

When the stack of envelops is exhausted, and the last envelop passes said controlling arm or lever 204, and is stamped and discharged from the machine, said controlling 100 arm falls upon the slat of the bed of the machine, beneath the arm, and the catch 196 is forced into engagement with the rear end of the notch 195, in the track plate 188, which is 105

now released from the action of the roller 200, and the stamp-feeding and stamp-affixing devices again become inactive.

When the pitman 164, on the arm 167, which actuates the carrier 147, and the stamp feeders, moves the carrier to the end of a forward movement, any variability in such movement, which would result in cutting the stamp from the strip of stamp-material, either forward or in rear of the perforated portions, is effectually prevented by the gage bar 212, which acts to control the movement of the arm 167, on the rock shaft 166, the precise distance between the perforated portions of the stamp material, occupied by the stamp, hence a rearward movement of the arm 167 operated by the pitman will cause the points of the stamp-feeders to move rearwardly the same distance, and the arm 167 may be adjusted on shaft 166 accordingly, the adjustment being facilitated by the sight opening 162, on the hood, by means of which the position of the feeders may be seen upon the retraction of the carrier 147, within the hood 152.

The supporting plate 80, for the stack of envelopes, which is above the path of travel of the envelope-feeding plate, is adjustable in a direction corresponding to the direction of movement of said feeding plate, and thus provides for envelopes varying in width, by releasing the adjusting nut 84, and moving the plate 80 forwardly or rearwardly, as the adjustment may be required, the slot 82, in plate 80, permitting such adjustment.

Such modifications of the invention may be employed as are within the scope of the appended claims.

1. In a stamp-affixing machine for envelopes, the combination with the frame of the machine, and the stamp-feeding and affixing devices, and with envelope-feeding means for feeding the envelopes in the direction of said devices, of a transverse envelop supporting plate connected fixedly with the side members of said frame, a horizontal envelop supporting plate adjustable in position toward said transverse fixed plate, and adjustable envelop-holders on said adjustable plate.

2. In a stamp-affixing machine for envelopes, the combination with the frame of the machine, and the stamp-affixing devices, and with a reciprocating carriage on said machine, and an envelope-feeding plate on said carriage, of a liquid-holding receptacle pivotally connected with said frame, a moistening device in said liquid-holding receptacle adapted to come into contact with the envelope-feeding plate in the reciprocal movements of said carriage, and adjustable supporting devices for said receptacle.

3. In a stamp-affixing machine for envelopes, the combination with the frame of the machine and the stamp-affixing devices,

and with means for feeding the envelopes in succession to said devices, of a moistening receptacle above the path of movement of the envelopes, and adjustable yielding supports on said frame for the moistening receptacle.

4. In a stamp-affixing machine for envelopes, the combination with the frame of the machine, and the stamp-affixing devices, and with a reciprocating envelop-feeder for feeding envelopes to said devices, of a liquid-holding receptacle beneath the said envelop feeder having a transverse opening in its top member adjacent its forward end, and a moistening roller in said opening journaled in the side members of said receptacle, a pivotal support for one end of said receptacle upon said frame, and adjustable supporting means for the other end of said receptacle.

5. In a stamp-affixing machine for envelopes, the combination with the frame of the machine, and the stamp-affixing devices, and with a reciprocating envelop feeder for feeding the envelopes to said devices, of a liquid-holding receptacle beneath the path of travel of the said envelop feeder having a transverse opening in the top member of said receptacle adjacent its forward end, and a moistening roller within said opening and journaled in the respective side members of said receptacle, a pivotal support for the forward end of said receptacle on said frame, a rock shaft on said frame, arms on said rock shaft supporting the rear end portion of said receptacle, and adjusting means on said frame connected with one of said arms.

6. In a stamp-affixing machine for envelopes, the combination with the stamp-affixing devices, of a reciprocating carriage movable in the direction of said devices, and a number of envelop-engaging, yielding finger bars upon said carriage, which are adapted to feed the envelopes in succession and are automatically depressed beneath the envelope in a return movement of the reciprocating carriage.

7. In a stamp-affixing machine for envelopes, the combination with the stamp-affixing devices, and with a reciprocating carriage movable in the direction of said devices, and with a transverse rocking member carried by said carriage, envelop-engaging finger bars upon said rocking bar, and means upon said bar and the frame of the machine acting automatically to move said bars in an upward position to engage the envelopes in the forward movement of the carriage, and in a downward position in the rearward movement of said carriage.

8. In a stamp-affixing machine for envelopes, the combination with the frame of the machine, and the stamp-affixing devices, of a reciprocating carriage movable in the direction of said devices, a transverse rocking member on said carriage, an envelop-feed-

- ing finger bar connected at its forward end with said rocking member, an arm on said rocking member and a pin on said arm, and automatically-acting tripping plates pivoted 5 at one end to the frame of the machine and supported in the direction of their free ends in the path of movement of said arm and having downwardly curved portions of said free ends adapted to trip said arm in the 10 reciprocal movements of said carriage.
9. A mechanism for operating the envelop-feeding finger bars in stamp-affixing machines, comprising a stamp-affixing device, a reciprocating envelop-feeding member, and a rocking device thereon, and a finger bar on said device, an arm on said rocking device, and a pin on said arm, a tripping plate in the path of movement of the pin on said arm pivotally supported at 15 one end and having a downwardly-curved tripping portion at the other end, and a support for the tripping plate between said ends.
10. In a stamp-affixing machine for envelops, the combination with the frame of the machine, and the stamp-affixing devices, of a reciprocating carriage movable in the direction of said devices, transverse rocking bars or slats upon said carriage, and envelop-feeding finger bars connected with 20 said bars, arms on said bars, and pins at the ends of said arms, tripping plates pivotally connected at their forward ends with the side members of the frame of the machine in the path of movement of the pins 25 on said arms and having downwardly-inclined rear ends, and supporting devices on the side member of said frame supporting the intermediate portions of the tripping 30 plates.
11. In a stamp-affixing machine for envelops, the combination with the frame of the machine, and the stamp-separating and affixing devices, and with feeding means for 35 feeding the envelops in succession to the said devices, of one or more envelop-retaining devices for retaining the envelop from a reverse movement and adjustable in the 40 direction of said stamp-separating and affixing devices.
12. In a stamp-affixing machine for envelops, the combination with the frame of the machine and its bed plates, and the stamp-separating and affixing devices, and with an envelop-feeding reciprocating carriage 45 movable in the direction of said devices, of a transverse bar pivotally connected with the side members of said frame, arms on said bar, and envelop-retaining plates in 50 the path of movement of the envelop-feeding carriage adjustably connected with said arms, and means for adjusting the position of said arms relative to the bed plates.
13. In a stamp-affixing machine for envelops, the combination with the frame of 55 the machine, and the stamp-affixing devices and with means for feeding the envelops to said devices, of a transverse bar pivotally connected with the respective side members of said frame, envelop retarding arms on 60 said bar, and plates carried by said arms having openings adapted to receive said arms, said plates having envelop-retarding notches in their forward portions, and adjusting devices for said plates upon said 65 arms.
14. In a stamp-affixing machine for envelops, the combination with the frame of the machine, and the stamp-affixing devices, a transverse rocking bar pivotally connected 70 with the respective sides of said frame, arms on said bar, and adjustable envelop-retaining devices on said arms, and means for effecting an adjustment rotatively of said transverse rocking bar.
15. In a stamp-affixing machine for envelops, the combination with the frame of the machine, and the stamp-affixing devices and with means for feeding the envelops to said devices, of a transverse rocking bar pivotally connected with the side members of said frame, adjustable envelop-retarding devices upon said bar in the path of movement 75 of the envelops in the direction of said devices, an arm on said bar, and an arm supporting plate on the side member of said frame beneath said arm, and an adjusting screw on said arm bearing on said arm supporting plate.
16. In a stamp-affixing machine for envelops, the combination with the frame of the machine and its bed, and with the stamp-affixing devices, of an envelop-feeding reciprocating carriage movable above the bed of the machine in the direction of 80 said stamp-affixing devices, and flap-moistening means for the flaps of the envelops, on said carriage, transverse shafts on the frame of the machine, and arms on said shaft, and longitudinal flap-sealing plates 85 on said shafts connected with said arms.
17. In a stamp-affixing machine for envelops, the combination with the frame of the machine and the stamp affixing devices, and with a guide plate for supporting the strip of stamp material, of a supporting plate on said guide plate and a reel for the stamp material, and a spring plate thereon over which the material on said supporting plate is fed from the reel.
18. In a stamp-affixing machine for envelops, the combination with the frame of the machine, and the stamp-feeding and affixing devices, of a guide plate for the strip of stamp material supporting the stamp-feeding devices, supporting means on said guide plate for the roll of stamp material, and a spring plate on said supporting means over which the material is fed.
19. In a stamp-affixing machine for envelops,

- velops, the combination with the stamp-feeding and stamp-affixing devices, and with an envelop-feeding reciprocating carriage, of means actuated synchronically by the carriage in a movement toward said stamp affixing devices co-acting therewith to impart motion to the stamp-feeding devices. 5
20. In a stamp-affixing machine for envelopes, the combination with the frame of the machine, and the stamp-feeding and stamp-affixing devices, and with a reciprocating envelop-feeding carriage movable in the direction of the said devices, of a rock shaft on said frame, means on the rock shaft for operating the stamp-feeding devices, and means in the path of movement of the reciprocating carriage actuating the rock shaft in a rocking movement. 10
21. In a stamp-affixing machine for envelopes, the combination with the frame of the machine, and the stamp-feeding devices, and with a reciprocating envelop-feeding carriage, of a rock shaft on said frame, means on said shaft for operating the stamp-feeding devices, and a lever arm pivoted to said frame, and having a curved free end in the path of movement of the reciprocating carriage, and an arm on said rock shaft actuated by said lever arm in the movement of said carriage toward the stamp-feeding devices. 15
22. The combination, with the stamp feeding devices, and the stamp separating and affixing devices, and with a lever supporting the latter devices, and with means for feeding the envelope to said stamp separating and affixing devices, of means co-acting automatically with the said lever for effecting a predetermined cessation of its movement during a forward material feeding movement of the stamp feeders, whereby a regulation is effected of the feed of the stamp material to the stamp separating and affixing devices. 20
23. In a stamp-feeding and affixing machine for envelopes, the combination with the stamp feeders and the stamp-affixing devices, and with a rock shaft, and connections thereon actuating the stamp feeders, of means for actuating the rock shaft, and means controlled by the rock shaft for governing the movement of the stamp feeders toward the stamp-affixing devices. 25
24. In a stamp-affixing machine for envelopes, the combination with the stamp-feeding and stamp-affixing devices, of a rock shaft, an arm on said shaft actuating the stamp-feeding devices, a separate adjustable arm on the rock shaft, and controlling means connected therewith, and the stamp-affixing devices for controlling the movement of the stamp-feeding devices. 30
25. In a mechanism for stamp-affixing machines for envelopes, a stamp-separating
- and affixing pivoted lever arm, and stamp feeders movable toward said lever arm, a rock shaft, an arm on said shaft, and a pitman on said arm pivoted to said stamp feeders, and a separate adjustable arm on the rock shaft, and a controlling bar pivoted at one end thereto and having a notch in its outer end, engaging with the pivoted stamp-separating and affixing lever arm. 35
26. In a mechanism for stamp-affixing machines for envelopes, a stamp-separating and affixing pivoted lever arm, and stamp feeders movable toward said lever arm, a rock shaft, an adjustable arm on said shaft, and a pitman connected with said arm and pivoted to said stamp feeders, and a separate arm on the rock shaft, and a controlling bar pivoted at one end thereto and having a notch in the other end engaging with the pivoted stamp-separating and affixing lever arm, and an adjusting arm on said bar. 40
27. In a mechanism for stamp-affixing machines for envelopes, a stamp-separating and affixing pivoted lever arm, and stamp feeders movable toward the lever arm, a rock shaft, an adjustable arm on said shaft, and a pitman connected with said arm and pivoted to said stamp feeders, and a separate arm on the rock shaft, and a controlling bar pivoted at one end thereto and having a notch in its outer end for engaging with the lever arm, a fixed support for the said bar, and a gage arm of bar adjustable between said fixed support and the notched end of said bar. 45
28. In a stamp-affixing machine for envelopes, the combination with the frame of the machine, and the stamp-affixing devices, a supporting plate for the strip of stamp material, a stationary hood on said plate, a carrier movable within said hood, and stamp feeders connected with said carrier, and means for operating said carrier. 50
29. In a stamp-affixing machine for envelopes, the combination with the frame of the machine, and the stamp-affixing devices, a supporting plate for the stamp material, a stationary hood on said plate, and a carrier movable within said hood, and feeders for the stamp material connected with the carrier, a rock shaft, an arm on said shaft, and a pitman pivotally connected with said arm and said carrier. 55
30. In a stamp affixing machine for envelopes, the combination with the reciprocating envelop feeding carriage, and a pivoted stamp affixing lever arm, and with means for imparting an upward movement to the said arm, of means on the said carriage in its movement toward said lever arm for imparting a downward movement to said lever arm. 60
31. In a stamp affixing machine for envelopes, the combination with a stamp affixing pivoted lever arm, and with a reciprocating envelop feeding carriage movable to, 65

ward said stamp affixing lever arm, of a yielding track plate, means for connecting said lever arm operatively with the said track plate, and devices on the envelop feeding carriage movable over the track plate to depress the pivoted stamp affixing lever arm.

32. In a stamp-affixing machine for envelops, the combination with a stamp-affixing pivoted lever, and with a reciprocating envelop-feeding carriage, of a track plate, a rod, pivotally connected with the lever arm and extending through one end of the track plate, a spring on said rod supporting said 15 end of the track plate, and a catch plate engaging the other end of said plate, a roller on the carriage movable over the plate in one direction of movement when the catch is released, and beneath said catch plate 20 when disengaged from the catch plate.

33. In a stamp-affixing machine for envelops, the combination with the frame of the machine, and the side members, of a pivoted stamp-affixing lever arm, a reciprocating envelop-feeding carriage movable toward said lever arm, a track plate having guide flanges, and retaining devices therefor on the side member of said frame, a rod pivoted to said lever arm extending through one 30 end of the track plate and having a notch in the other end, a coiled spring on said rod beneath said track plate, and a self-engaging pivoted catch plate on the side member of the frame, means for disengaging the catch plate, and a roller on the reciprocating carriage movable upon the upper surface of the track plate in one direction of movement and beneath the track plate in another direction.

40 34. In a mechanism for stamp-affixing machines for envelops, a pivoted stamp-affixing lever arm, and a reciprocating envelop-feeding carriage, a roller on said carriage, and a track plate in the path of said roller, an operating rod pivotally connected with the stamp-affixing lever arm and extending through one end of the track plate, a self-acting pivoted catch plate engaging with the other end of the track plate, a spring 45 on said rod supporting the track plate normally above the path of travel of said roller on the reciprocating carriage, and a tension-adjusting device for said spring.

35. In a mechanism for stamp-affixing 55 machines for envelops, a stamp-affixing pivoted lever arm, and a reciprocating envelop-feeding carriage, a track plate having an opening in one end, and an operating rod pivoted to said lever and extending through

said opening in the track plate, a lug 60 through which the lower end of said rod extends, a sleeve on said rod, and a coiled spring extending around said sleeve and movable with the sleeve through the opening in the track plate and bearing on said lug, an adjusting nut on the rod beneath the lug, and an adjusting nut on said rod above the sleeve against which the upper end of the spring is adapted to bear, and a separate spring supporting said track plate bearing 70 on the adjusting nut above the sleeve, a self-engaging catch for the other end of said track plate, and a releasing means therefor, and a roller on said reciprocating carriage movable in one direction over the track plate 75 and beneath the track plate in the other direction.

36. In a stamp-affixing machine for envelops, the combination with the frame of the machine, and the bed plate, and the 80 stamp-affixing devices, and with a reciprocating envelop-feeding carriage, of a rock shaft on said frame of the machine, and a controlling arm thereon normally bearing on the bed plate of the machine, a movable 85 track plate on the side member of said frame having track-guiding flanges, and retaining devices thereon on said side member, an operating rod pivoted to said stamp-affixing lever arm and extending through one end of 90 the track plate, and a spring on said rod supporting said end of the track plate, a pivoted self-engaging catch engaging the other end of the track plate, an arm on said rock shaft, and a catch-releasing lever pivoted to said arm and operatively connected with said catch plate, a depending bar on said reciprocating carriage, and a roller on said bar movable upon the track plate when the catch plate is released, and beneath the 100 track plate when engaged by the catch plate.

37. In a stamp-affixing machine for envelops, the combination with the stamp-feeding and stamp-affixing devices, and with means for feeding the envelops to said devices, and with means for imparting motion synchronically to said devices, of a rock shaft, mechanism controlled by the rock shaft for controlling the movement of the stamp-feeding and affixing devices, and a 105 controlling arm in the path of movement of the envelops controlling the movement of the rock shaft and adjustable thereon.
